US00D739656S

(12) **United States Design Patent** (10) **Patent No.:** **US D739,656 S**
Krotts (45) **Date of Patent:** **** Sep. 29, 2015**

(54) **COLLAPSIBLE STRUCTURE**(71) Applicant: **Bajer Design & Marketing, Inc.**,
Waukesha, WI (US)(72) Inventor: **Dean B. Krotts**, Hartland, WI (US)(73) Assignee: **Bajer Design & Marketing, Inc.**,
Waukesha, WI (US)(**) Term: **14 Years**(21) Appl. No.: **29/520,558**(22) Filed: **Mar. 16, 2015**

S.C.**CLAIM**The ornamental design for a collapsible structure, as shown
and described.**DESCRIPTION**

FIG. 1 is a perspective view of the embodiment;
 FIG. 2 is a right side elevation view, the left side elevation
 view being identical;
 FIG. 3 is a front elevation view, the rear elevation view being
 identical;
 FIG. 4 is a top plan view; and,
 FIG. 5 is a bottom plan view.
